GRINDING MACHINE

William Ogilvie, Knowle, England, assignor to
B. S. A. Tools Limited, Birmingham, England,
a British company

Application April 4, 1936, Serial No. 72,785
In Great Britain April 13, 1935

8 Claims. (Cl. 125—11)

This invention relates to improvements in machines for grinding cylindrical bodies, of the kind wherein the work to be ground is supported between the co-acting faces of peripherally opposed grinding and control wheels, and refers more particularly to wheel trueing mechanism of the kind wherein a diamond or other cutting device is carried on a transversely movable slide, adapted to be reciprocated by any suitable means, whereby the cutter is caused to traverse across the periphery of the grinding or the control wheel to effect the trueing of same, the said slide being carried on a longitudinally movable slide mounted on the hood or cover of the control wheel or the grinding wheel.

The object of the invention is to provide, in combination with trueing mechanism of the aforesaid kind, a form trueing mechanism whereby the peripheries of the grinding wheel and the control wheel can be automatically shaped or trued to any desired shape conforming with the shape or form of the cylindrical body it is desired to be ground. The term "cylindrical" as herein employed to define the type of body to be ground, is intended to include bodies of rotation other than true cylinders, i. e. bodies of rotation which are figured or vary in circumference along their length.

According to this invention, as applied to trueing mechanism of the aforesaid kind, wherein a diamond cutter or other trueing device is carried on a transversely movable slide adapted to have imparted thereto a reciprocating movement whereby the cutter is caused to traverse across the periphery of the grinding or the control wheel to effect the trueing of same, and wherein said slide is carried on a longitudinally movable slide to provide adjustment and infree of the cutter, means are provided whereby the grinding and/or control wheel can be automatically trued to any desired shape conforming with the shape of the cylindrical body to be ground, characterized by the provision and use of a pair of formers, a tracer arranged for engagement with either of the formers, and spring loaded means whereby a former and the tracer are held in operative contact during the traversing movement of the cutter whereby a combined longitudinal and sideway movement is imparted to the cutter, said movement conforming with the shape or form of the cylindrical body desired to be ground.

The invention also consists in means whereby the spring which controls the movement of the slide and holds the former in operative contact

with the fixed tracer, can be locked or made inoperative and the former held clear of engagement with the tracer, to permit of the use of the trueing device in the ordinary way for effecting the trueing of a plain face on the peripheries of the grinding and the control wheels.

The invention also consists in the provision of means which are adapted to enable the operator to manually assist the action of the mechanism in imparting movement to the slide when the tracer is passing over a steep angle on the former.

Two constructions according to this invention are illustrated in the accompanying drawings by way of example, in which:—

Figure 1 shows a side elevation of the upper part of a centreless grinding machine provided with one arrangement of form trueing mechanism, constructed in accordance with this invention.

Figures 2 and 3 show respectively, on an enlarged scale, a part sectional side elevation and a plan view of the form trueing mechanism.

Figure 4 shows, on a further enlarged scale, an end elevation and a part sectional view taken on line A—A, Figure 5.

Figure 5 shows a side elevation of the form trueing mechanism in conjunction with manually operable means adapted to assist the action of the former in imparting movement to the slide.

Figures 6 and 6a, respectively, are a plan view and an end elevation of one convenient arrangement of former.

Figure 7 is a longitudinal sectional view through the diamond holder structure.

Figure 8 is a cross section taken on the plane 35 of line 8—8 of Figure 7; and

Figures 9 and 10 show respectively a part sectional side elevation and a plan view of a modified construction of form trueing mechanism.

Figure 11 is a plan view of the tracer bar.

According to one practical mode of carrying the invention into effect, as illustrated in Figures 1 to 5, I mount on the lower part of a transversely movable slide 1 carrying the holder 2 for a diamond or other trueing element 2a, a pair of formers 3 and 4, one being adapted for the form trueing of the periphery of the grinding wheel 5 and the other for the control wheel 6. A longitudinally movable slide is employed at 7. Said slides 1 and 7 are mounted or supported in a manner common in machine tool design, that is, slide 1, as best seen in Figure 2, has a longitudinal dove-tail slot 1h engaged with a correspondingly formed slide member 1i carried by an angularly adjustable bracket 8, while slide 7, as best shown in

Figure 4, has a dove-tail slide means $7h$ engaged in a correspondingly formed slot $7i$ in the hood or cover 14 of the aforesaid control wheel 6 . In a longitudinal slot $7a$ formed in said slide 7 is mounted a rectangular bar 9 which carries at its front end a tracer $9'$ provided with a nose or projection 10 . In the rear end of said bar 9 is mounted an adjusting screw 11 which is longitudinally confined in an open ended slot 12 formed in one end of a block member 13 slidably attached to the hood as seen in Fig. 4. Said adjusting screw 11 is reduced in diameter by means of a circumferential groove 15 arranged to engage the said slot 12 as seen in Figs. 2 and 3. The said block member 13 is further adapted to be released and moved clear of engagement with the said adjusting screw 11 to permit of withdrawal of the tracer bar 9 , to allow of the turning of the tracer to a position for engagement with the other former. The said formers 3 and 4 are mounted and disposed in a recess $3c$ in the lower part of the movable slide 1 one above the other, and as previously stated, one is adapted for the trueing of the grinding wheel 5 , and the other for trueing the control wheel 6 . In the arrangement illustrated, as seen in Figure 2, the tracer $9'$ is arranged for its nose or projection 10 to engage with the upper former 3 , and the diamond holder 2 is moved or turned to the position for the trueing of the control wheel 6 . In Figure 1 the tracer $9'$ is shown turned to the position for engagement with the lower former 4 , and the diamond holder 2 in the position for trueing the grinding wheel 5 .

The diamond holder 2 (Figs. 7 and 8) is mounted in a cylindrical housing 50 on the front part of the transversely movable slide 1 , in which it is capable of being adjusted vertically and also turned to bring the diamond tool into a position for contact with the grinding wheel 5 or the control wheel 6 . In the stem part 51 of the diamond holder on opposite sides thereof, are formed longitudinal slots 52 and 53 , adapted to be engaged by a bolt 54 , screw-threaded in housing 50 , and on the upper part of the said stem part 51 is formed a screw-thread 56 engaged by a nut 55 .

Nut 55 is carried by a tubular head 57 swivelled at 58 in the housing 50 and operable manually through the aid of a device 59 which also functions for rigidly clamping the diamond holder in either position to which it may be turned or adjusted.

When it is desired to turn the diamond tool through 180 degrees to move it from the position for contact with say the grinding wheel 5 to the position for contact with the control wheel 6 , the bolt 54 is first withdrawn from engagement with the slot 52 , thus permitting of the diamond holder being given a half turn bringing the other slot 53 into alignment with the bolt 54 , which can then be moved into engagement with said slot 53 .

The groove $51a$ around the stem part 51 is provided for ease in the manufacture of this part.

In order to make the tracer adaptable for engagement with either one of the formers 3 and 4 , which are disposed one above the other, the nose or projection 10 of the tracer $9'$ is disposed eccentric to or out of centre with its attachment stem 22 , as seen in Figures 1 and 2, so that by a half turning movement of the tracer $9'$, after removal of the tracer bar 9 , its nose or projection 10 can be brought into alignment with the other former. Alternatively, the tracer $9'$ may be fixed and its nose or projection 10 so disposed in relation to the centre of the tracer bar

9 that by removal of the latter and a half turning movement before replacing same, its nose or projection 10 will be brought into alignment with the other former.

The rear end of the tracer bar 9 is bored at $9b$ to receive the rotatable but longitudinally confined adjusting screw 11 , and a vertical opening 16 is formed in said bar 9 in which is located and non-rotatably housed a nut 17 engaged by the said adjusting screw 11 , which latter, upon being rotated, will impart a sliding movement to the tracer bar 9 for the purpose of adjusting the nose or projection 10 in relation to either of the formers 3 or 4 . If desired, the tracer bar 9 may be slotted at $9a$ to lighten same and provide a passage for the inner end of screw 11 .

In order to allow of the ready removal of the tracer bar 9 , to permit of the turning of the tracer $9'$ for the purpose previously described, the member 13 , in which is formed the open ended slot 12 arranged to engage with the circumferential groove 15 in the adjusting screw 11 , is slidably carried on the bracket 18 secured to the end of the hood or cover 14 of the control wheel, the said member 13 being fixed in its operative position by a bolt 20 engaging with a slot 21 formed in said member, so that by releasing the said bolt 20 and sliding the member 13 sideways, it is freed from engagement with the adjusting screw 11 of the tracer bar 9 and the latter can then be withdrawn to permit of the tracer being turned to bring its nose or projection 10 into alignment with the second former, or for the purpose of substituting another shape or form of tracer, such as one provided with a different shape of nose or projection 10 .

The means whereby the longitudinally movable slide 7 is spring loaded for the purpose of holding the formers 3 or 4 in sliding engagement with the tracer, in a convenient arrangement comprises an adjusting screw 23 engaging with a nut 24 mounted in a lug or bracket 25 formed or fixed on the underside of said slide, the said screw 23 having fitted thereto a rotatable but longitudinally confined plain sleeve part 26 which is slidably carried in the bracket 18 fixed to the hood or cover 14 of the control wheel 6 , and between the said bracket 18 and a fixed collar 28 mounted on the outer end of the aforesaid adjusting screw 23 is located a compression spring 29 which normally tends to move the slide 7 and hold either of the formers 3 or 4 in engagement with the fixed tracer $9'$.

Means are provided whereby the aforesaid adjusting screw 23 can be clamped to its bracket 18 and prevented from longitudinal movement, thus making inoperative its spring 29 , as for instance when it is desired to dispense with the use of the formers 3 and 4 , and employ the trueing device $2a$ for the producing or trueing of a straight face on the periphery of the grinding wheel 5 or the control wheel 6 . In the fixed bracket 18 , as seen in Figure 4, is mounted a clamping pad or sleeve 30 actuated by a suitable knob or nut 31 engaging with a screw-threaded stem part 32 of the said clamping pad, whereby it can be made to grip the sleeve 26 in which the adjusting screw 23 is rotatably carried and longitudinally confined, and thus prevent the spring 29 imparting movement to the slide 7 , but in this position, rotation of the adjusting screw 23 is adapted to impart movement to the slide 7 for adjustment of the diamond cutter $2a$ when employed for straight trueing of the grinding wheel 5 and control wheel 6 . The screw 23 is also

adapted when clamped and prevented from longitudinal movement to serve for positioning the diamond tool holder 2 in relation to the periphery of the grinding or the control wheel.

5 Means are provided to augment the effort of the spring 29 in moving the slide 7 when a steep angle on one of the formers 3 or 4 is being negotiated by the tracer, which in one convenient arrangement, as seen in Figures 4 and 5, comprise the provision of a rack and pinion device, wherein the rack 33 is mounted on the edge of the slide 7 and engaged by a pinion 34 pivoted to the side of the hood or cover 14 of the control wheel 6 and provided with a hand lever 35 or 10 other suitable operating means.

15 The mode of operation is as follows: Assuming it is desired to shape the periphery of the grinding wheel 5 to any desired configuration conforming to the shape of the body to be ground, the diamond holder 2 is adapted to be turned so that the diamond or like tool 2a may assume a position facing either the grinding wheel 5 or the control wheel 6 and adjusted vertically if necessary.

20 The adjusting screw 23 is first prevented from longitudinal movement by turning the clamping nut 31 whereby the clamping pad 30 is caused to grip the sleeve part 26 which is longitudinally confined on said screw. A turning movement of the 25 adjusting screw 23 will then bring the dressing tool into contact with the periphery of the grinding wheel 5. The tracer bar 9, which may have been previously retracted, is then adjusted by turning the adjusting screw 11 which engages with the nut 17, non-rotatably housed in said bar, to bring the tracer 9 at nose or projection 10 into contact with the former 4, which is of a shape corresponding to the desired shape of the grinding wheel 5. The clamping nut 31 is then turned to release the clamping pad 30 and permit of inward longitudinal movement of the sleeve 26 and the adjusting screw 23, when the latter is turned, whereby the spring 29 may be loaded or compressed to any desired degree, for the purpose of imparting an inward and outward movement to the slide 7, when a transverse movement is imparted to the slide 1 carrying the diamond tool holder 2, by any known means, in the operation of dressing or truing of the wheel 5, such 30 as a feed screw housed in the bracket part 8, engaging with a nut on the slide 1, the said screw being rotated by a handle or other means. In the process of shaping the periphery of the grinding wheel 5, during the transverse movement of the dressing tool 2a, it will be readily understood that as the former 4 passes over the nose 10, the said parts are held in sliding contact under the influence of the spring 29, which causes the slide 7 to have imparted thereto, during the transverse 35 movement of the slide 1 and diamond holder 2, a slight backward and forward longitudinal movement according to the shape of the former 4.

40 When it is desired to shape the periphery of the control wheel 6, the tracer bar 9 is removed by first slackening the bolt 20, shown in Figs. 3 and 4, which permits of the block 13 being moved sideways to withdraw the slot 12 therein from engagement with the circumferential groove 15 formed in the adjusting screw 11, thus permitting 45 of the complete withdrawal of the tracer bar 9. The tracer 9 is then given a half turn movement which brings its nose 10 into alignment for engagement with the upper former 3, which is of such shape that it is desired to form the periphery of the control wheel or wheels 6.

50 The tracer bar 9 and its adjusting screw 11 are again re-assembled and fixed in operative position by inward movement of the block 13 mounted on the fixed bracket 18, into engagement with the groove 15 in the adjusting screw 11. The diamond tool holder 2 is given a half turn movement to bring the dressing tool 2a into the position facing the control wheel 6, and is then moved into contact therewith as shown in Fig. 2, and the spring 29 is then tensioned or 55 loaded in the manner as previously described.

60 During the process of shaping or truing the periphery of the control wheel 6, the dressing tool 2a can be advanced as required by turning the adjusting screw 11 in a clock-wise direction, when 15 it has a right hand screw thereon, but when shaping or truing the grinding wheel 5, it will be readily understood that the said adjusting screw 11 has to be turned in an opposite or anti-clock-wise direction. The screw thread of screw 11 may 20 be either right or left hand.

65 In the modified construction and arrangement shown in Figures 9 and 10, the transversely movable slide 1a carrying the diamond tool holder 2a is mounted on the front part 36 of a longitudinally movable slide 37 mounted on an angularly adjustable bracket 38 attached to the upper face of a lower longitudinally movable slide 7a mounted on the control wheel head 14a. The angularly adjustable bracket 38 is attached to 30 the slide 1a by a pivot 39 and is fixed to the slide 1a by a clamping bolt 40 fixed to the said bracket and engaging with a segmental slot 41 in the end of the slide 1a. When the formers 3a and 4a are employed for the automatic trueing of the grinding or the control wheel, the angularly adjustable bracket 38 is moved to and fixed in a central position, as seen in Figure 10, against a stop 42 (Fig. 10), in which position it is securely fixed by the clamping nut 43. The angular adjustment of the bracket 38 is only intended for use in known manner when it is desired to cut a straight taper or an inclined face on the grinding or the control wheel 6a, without the use of the formers 3a and 4a.

70 The formers 3a and 4a are mounted on the upper rear part of the transversely movable slide 1a. On a lug or projection 38a on the angularly adjustable bracket 38 is mounted an attachment plate 44, in which is carried a tracer provided with a nose or projection 10a disposed eccentric to or out of centre with its attachment stem 22a so that a half turn movement of the tracer will bring its nose or projection 10a into alignment with either one of the formers 3a or 4a. On the inner face of the head of the tracer is formed a rib or register 45 arranged to engage with a corresponding slot or gap formed in the front face of the attachment plate 44 in which it is held in engagement by the clamping nut 46 mounted on 60 the screw-threaded outer end of the stem part 22a of the tracer.

75 In the arrangement illustrated in Figures 9 and 10, the nose or projection 10a of the tracer is shown engaging with the lower former 4a, and the diamond holder 2a is shown turned to the position for the diamond or like tool being used for trueing or shaping the periphery of the control wheel 6a. It will be readily understood that when it is desired to true or alter the shape of 80 the periphery of the grinding wheel, it is simply necessary to slacken the clamping nut 46, which permits of the tracer being moved forward to release its rib or register 45 from engagement with its slot in the attachment plate 44, when a half 75

turn movement will bring its nose or projection 10a into alignment with the upper former 3a, in which position it can then be securely fixed by means of the clamping nut 46, ready for the 5 trueing or shaping of the grinding wheel, after having given a half turn movement to the diamond tool 2a.

The means whereby the nose or projection 10a of the tracer is held in operative contact with 10 either one of the formers 3a or 4a during the longitudinal traversing movement of the cutter, whereby the latter has imparted thereto a combined longitudinal and sideway movement, in the modified construction, comprises a loading spring 15 29a located between the lug 38a on the angularly adjustable bracket 38 fixed to the slide 1a, and a bearing sleeve 47 mounted in the outer end of the slide 37 which has mounted on its front part 36 the transversely movable slide 1a. The bracket 20 38 and the slide 37 are connected by an adjusting screw 23a engaging with a nut 24a non-rotatably housed in a vertical slot formed in the said bracket 38, the said screw having fitted rotatably thereon a plain sleeve part 26a which is 25 longitudinally fixed between a collar formed on the screw and a collar 28a mounted on the outer end thereof, the said sleeve 26a being adapted to slidably engage with the bearing sleeve 47 fixed in the upper slide 37.

30 Means are provided whereby the aforesaid adjusting screw 23a can be clamped to the slide 37 and prevented from longitudinal movement in relation thereto, thus making inoperative the spring 29a, when it is desired to dispense with 35 the use of the formers 3a or 4a and employ the trueing device for producing or trueing a straight face on the periphery of the grinding or the control wheel, said means in one convenient arrangement comprising a clamping pad or sleeve 30a, like that at 30, mounted in a slot formed in the 40 upper slide 37, and arranged to grip the sleeve 26a, said pad being provided with a screw-threaded stem part 32a, and a clamping nut 31a. When the said sleeve 26a is clamped and prevented from longitudinal movement, rotation of 45 the adjusting screw 23a will impart movement to the upper slide 37, together with the transverse slide 1a, thus separating the formers from the tracer to permit of removal or replacement of 50 said formers, or allow of the reversing of the position of the tracer from its position in alignment with the one former to the position for engagement with the other former, and further to hold the tracer and former separated, when it is 55 desired to use the trueing mechanism for trueing or forming a straight face on the periphery of the grinding or the control wheel.

In a plate 48 attached to the control wheel head 14a is mounted a rotatable and longitudinally confined infeed screw 49 engaging with a nut 50 non-rotatably mounted in a bracket 51 attached to the underside of the slide 1a. The said infeed screw 49 is adapted for use in positioning the diamond holder 2a and its cutter in 60 relation to the peripheries of either the grinding or the control wheels, and for applying the requisite feed movement to the cutter in the operation of trueing or shaping the wheels.

The mode of operation of the modified device 70 shown in Figures 9 and 10 is as follows: In the arrangement illustrated, the diamond tool holder 2a is turned to the position for shaping or trueing the control wheel 6a, while the tracer 10a is shown in engagement with the lower former 75 4a, under the influence of the spring 29a. In

this arrangement the lower former 4a is of a shape corresponding to the desired shape of the control wheel 6a. By rotation of the adjusting screw 49, the tool is brought into contact with the control wheel 6. When it is desired to shape 5 or true the grinding wheel, the diamond tool holder 2a is given a half turn movement, so that the cutter then faces the said grinding wheel. The adjusting screw 23a is then longitudinally confined on the slide 37 by means of the clamping nut 31a and pad 30a engaging the sleeve part 26a, so that by a turning movement of the said screw 23a, the tracer 10a can be retracted from engagement with the former 4a a sufficient distance to permit of a half turn movement being 10 given to the tracer 10a by first slackening the nut 46, which permits of the tracer being moved forward to release its rib or register 45, and then turned to bring its nose or projection 2a into alignment with the upper former 3a, which corresponds in shape to the shape it is desired to form on the periphery of the grinding wheel. When the clamping bolt 31a is released, the spring 29a will cause the slide 37 to move forward and bring the tracer 10a into operative engagement with the former 3a, the said parts being held in sliding contact, during transverse movement of the slide 1a, under the influence of the spring 29a, in the manner as previously described.

In the operation of trueing or shaping the grinding wheel and the control wheel 6a, the adjustment of the cut of the tool 2a can be effected by rotation of the adjusting screw 49.

What is claimed is:

1. In combination with a grinding machine 35 having a grinding wheel and an associated control wheel, a truing device for said wheels, a slide reciprocable transversely with respect to the periphery of said wheels, means to adjustably mount and position said truing device on said slide to 40 coact with either of said wheels, means providing former surfaces on said slide one individual to each of said wheels, a tracer, means adjustably mounting the tracer in relatively fixed relation to the slide for engagement with said former surfaces individually, and means to maintain following contact of the tracer with the adjacent former surface during movement of the slide.

2. In combination with a grinding machine 50 having a grinding wheel and an associated control wheel, a truing device for said wheels, a slide reciprocable transversely with respect to the periphery of said wheels, means to adjustably mount and position said truing device on said slide to coact with either of said wheels, means providing former surfaces on said slide one individual to each of said wheels, a tracer, means adjustably mounting the tracer in relatively fixed relation to the slide for engagement with said former surfaces individually, and spring-loaded 55 means maintaining contact of the tracer with the adjacent former surface during movement of the slide.

3. In combination with a grinding machine 65 having a grinding wheel and an associated control wheel, a truing device for said wheels, a slide reciprocable transversely with respect to the periphery of said wheels, means to adjustably mount and position said truing device on said slide to coact with either of said wheels, a pair of formers on said slide one individual to each of said wheels, a tracer, means adjustably mounting the tracer in relatively fixed relation to the slide for engagement with said former surfaces individually, and means to maintain following con- 70 75 80 85 90 95 96

tact of the tracer with the adjacent former surface during movement of the slide.

4. In combination with a grinding machine having a grinding wheel and an associated control wheel, a truing device for said wheels, a slide reciprocable transversely with respect to the periphery of said wheels, means to adjustably mount and position said truing device on said slide to coact with either of said wheels, a pair of superposed formers on said slide one individual to each of said wheels, a tracer, means adjustably mounting the tracer in relatively fixed relation to the slide for engagement with said former surfaces individually, and means to maintain following contact of the tracer with the adjacent former surface during movement of the slide.

5. In combination with a grinding machine having a grinding wheel and an associated control wheel, a truing device for said wheels, a slide reciprocable transversely with respect to the periphery of said wheels, means to adjustably mount and position said truing device on said slide to coact with either of said wheels, means providing former surfaces on said slide one individual to each of said wheels, a tracer, means adjustably mounting the tracer in relatively fixed relation to the slide for engagement with said former surfaces individually, means to maintain following contact of the tracer with the adjacent former surface during movement of the slide, and means operable to maintain the tracer retracted so as to be unaffected by either former surface.

6. In combination with a grinding machine having a grinding wheel and an associated control wheel, a truing device for said wheels, a slide reciprocable transversely with respect to the periphery of said wheels, means to adjustably mount and position said truing device on said slide to coact with either of said wheels, means providing former surfaces on said slide one individual to each of said wheels, a tracer, means adjustably mounting the tracer for variation of its angular position in relatively fixed relation

to the slide for engagement at different elevations with said former surfaces individually, and means to maintain following contact of the tracer with the adjacent former surface during movement of the slide.

7. In combination with a grinding machine having a grinding wheel and an associated control wheel, a truing device for said wheels, a slide reciprocable transversely with respect to the periphery of said wheels, a body mounting said slide, supporting means for the body, means to rotatably mount said truing device on said slide to coact with either of said wheels, a pair of superposed formers on said slide one individual to each of said wheels, a tracer structure on said support for engagement with said formers individually, spring means to maintain contact of the tracer structure with the adjacent former during transverse movement of the slide, screw means on the support and engaged with the body operable to adjust the position of the body, and screw means on the support and engaged with the tracer structure to adjust the position of the latter.

8. In combination with a grinding machine having a grinding wheel and an associated control wheel, a truing device for said wheels, a slide reciprocable transversely with respect to the periphery of said wheels, means to adjustably mount and position said truing device on said slide to coact with either of said wheels, means providing former surfaces on said slide one individual to each of said wheels, a tracer, means adjustably mounting the tracer in relatively fixed relation to the slide for engagement with said former surfaces individually, means to maintain following contact of the tracer with the adjacent former surface during movement of the slide, and rack and pinion means operable manually to impart movement to the slide when the tracer passes a steep angle on a former surface.

WILLIAM OGILVIE.
